PITMAN

Albert L. Durham, Hull, Tex.

Application October 16, 1933, Serial No. 693,796

2 Claims. (Cl. 74—579)

This invention relates to a pitman, and has more particular relation to that type of pitman specially adapted for connecting a walking beam to the crank arm of the power shaft.

5 Another object of the invention is to provide a pitman whose length can be readily varied.

A further object is to provide a sectional pitman whose sections are longitudinally adjustable relative to each other so that the pitman can 10 be collapsed when not in use. The pitman is specially adapted for use in connection with the walking beam of a pump operating mechanism, for connecting said beam to the power.

With the above and other objects in view the 15 invention has particular relation to certain novel features of construction, arrangement of parts and use, an example of which is given in this specification and illustrated in the accompanying drawing, wherein:

20 Figure 1 shows a longitudinal sectional view of the pitman.

Figure 2 shows a side view.

Figure 3 shows a fragmentary view partly in section, showing the pitman collapsed, and

25 Figure 4 shows a side elevation of a pump operating mechanism embodying the pitman.

In the drawing the numerals 1 and 2 designate the respective sections of the pitman, the latter of which is shown telescoped into the former.

30 The adjacent ends of said sections are provided one with an internal annular shoulder 3 and the other with a head 4, engageable with said shoulder to prevent the separation of the sections but to permit their relative longitudinal movement.

35 The section 1 has a stirrup 5 which is engageable over the corresponding end of the walking beam 6 and the opposite end of the section 2 is internally threaded to receive the externally threaded shank 7 which is screwed into the section 2 and a lock nut 8 is screwed onto said shank and abuts the corresponding end of the section 1.

40 The outer or free end of the shank 7 is provided with a yoke 9 to receive the sectional bearing 10 which is secured in said yoke by the wedge-like key 11. The power shaft 12 has a crank 13 thereon provided with a wrist 14 which works in the pitman bearing.

45 During the operation of the pump the weight of the pump rods will cause the downward movement of the corresponding end of the walking beam and the upward movement of the opposite end of said beam and upon upward movement of the pump rods the load is lifted by the power shaft and crank arm operating through said pitman. During this operation the sections 1 and

2 may be pinned together, if desired by the pin 15 which is fitted through the adjacent ends of the sections 1 and 2 as shown in Figure 1, although this pin is not indispensable as there will be very little if any relative movement of said sections during the normal operations of the pump.

5 At times it is necessary, when the pump is not being operated, to collapse the pitman so that it will not be in the way of the workmen who may find it necessary to work on or about the operating mechanism. In such case the sections of the pitman may be collapsed as shown in Figure 3. In such event the pin 15 may be inserted 10 through a suitable opening in the section 2 adjacent the head 4 above the upper end of and in position, to rest on, the upper end of the section 1 so as to hold the pitman collapsed and thus 15 elevated out of the way of the workman.

20 The drawing and description disclose what is now considered to be a preferred form of the invention by way of illustration only while the broad principle of the invention will be defined by the appended claims.

25 What I claim is:

1. A pitman formed of telescopically arranged sections, a shank having an adjustable connection with one section, said shank being provided with a wrist pin bearing, a yoke on the other section 30 shaped to receive a walking beam, one of said sections being tubular to receive the other section and having an inside shoulder, said other section having a head engageable with said shoulder and having a transverse pin bearing adjacent 35 the head, said sections being collapsible and a pin insertable through said pin bearing and engageable with the end of the other section when the pitman is in collapsed position.

2. A pitman formed of telescopically arranged 40 sections, a shank having an adjustable connection with one section, said shank being provided with a wrist pin bearing, means on the other section for attaching said other section to a walking beam, one of said sections being tubular to receive the other section and having an inside shoulder, said other section having a head engageable with said shoulder and having a transverse bearing adjacent the head, said sections 45 being collapsible and stop means insertable into said last mentioned bearing and engageable with the end of the other section when the pitman is in collapsed position.

50 ALBERT L. DURHAM. 55
